UNITED STATES PATENT OFFICE

FELIX MOREL, OF FAYETAS, PAR RAZAC-SUR-L'ISLE, FRANCE, ASSIGNOR TO ANCIENS
ETABLISSEMENTS R. CORNELY & CIE (SOCIETE ANONYME), OF PARIS, FRANCE

SEWING MACHINE

Application filed July 20, 1926, Serial No. 123,759, and in France March 23, 1926.

In my prior patent application Serial No. 698,800 filed March 12, 1924, I described a device for the direct and separate control of the movement of oscillation of each of the needles by means of elements which rotate exclusively about their axes, through the medium of a single initial cam and a single connecting rod, in order to impart the motion to the oscillating system itself. The said mechanism was defective from the fact that oscillations of the connecting rod did not take place in the vertical plane, since they made a certain angle with the plane of oscillation of the elements controlling the needle-carriers.

Further, the joints at the ends of the connecting rod consisted of ball-and-socket joints which were difficult to manufacture and required an accurate adjustment, and whereof the wear could not be taken up.

The forward movements of the needles could only be made exactly equal by properly proportioning the distance between their attaching points and their centres of oscillation, to the lengths of their controlling rods, and this proved somewhat difficult to carry out in practice.

In the improved controlling mechanism, the object of the present invention, all such disadvantages are obviated. In this device, the position of the connecting rod controlling the needles is changed, so that the rod will always oscillate in the vertical plane, and this allows the said rod to be mounted at each end by a cylindrical pivot joint which is easy to manufacture and to adjust.

Fig. 1 is a fragmentary side elevational view of the right end of my apparatus.

Fig. 2 is a view similar to Fig. 1 of the left end of my apparatus.

Fig. 3 is a detail view of the mechanism controlling the needles.

Fig. 4 is a side elevation of the said mechanism.

Fig. 5 is a horizontal section on the line 5-5 of Fig. 4.

Fig. 6 is a plan view, on a larger scale, of an arrangement for regulating the amplitude 50 of the oscillation.

Figs. 7 and 8 show two other embodiments of the invention respectively.

The main shaft 1 of the machine, Fig. 1, communicates its movement of rotation, through the medium of the gear wheels 2 and 3, to the cam 4 which rotates upon the intermediate shaft 5.

The cam 4 (Fig. 1) imparts to the connecting rod 9, by means of the two levers 6 and 7, and the link 8, the movements necessary for the oscillation of the needles.

The connecting rod 9 is rigidly connected with the sleeve 10 (Figs. 2 and 5), and it is guided in a cylindrical bearing 19 having the axis $y-y$, so as to allow it to assume sliding and rotary movements which are imparted to the shaft 20 by which the connecting rod 9 transmits its motion, due to the cam 4, to the links 12 and 13 which are also pivoted to the shaft 20.

The two links 12 and 13 are further pivoted to two levers 14 and 15 carrying at their ends the two respective pivoted bearings c and d in which are slidably the rods 16 and 17 forming a lever pivoting on the stud o and o' for the oscillation of the needles f and f' .

The said studs o and o' are fastened to the same support which is secured to the main needle-carrier 18 of the machine and which possesses, as in all sewing machines, a reciprocating motion in the vertical direction; the rods 16 and 17 which are actuated by the needle-carrier 18, slide in the bearings c and d of the levers 14 and 15.

The lever 14 is pivoted to a cylindrical stud e which is mounted on a boss formed on the cast iron head of the machine (Fig. 4). The stud e is hollow, in order that the lever 15 may in all cases pivot on the axis of the lever 14, so that these two levers will have the same pivoting axis. Any other suitable arrangement may be adopted for the axes of the levers 14 and 15, and these might be placed in line with one another.

It is observed that when the connecting rod 9 is given a horizontal reciprocating motion by the action of the cam 4 and the levers 6 and 7, the jointed parallelogram consisting of the links 12 and 13, the lever 15, and the

upper part of the lever 14, will open or close according to the movements of the connecting rod 9, so that the ends of the levers 13 and 14 will move from or towards the axis 5 of the needle-carrier 18; for this reason the rods 16 and 17, due to the bearings *c* and *d*, will impart to the needles the corresponding movement of oscillation.

Fig. 6 shows a detail of the arrangement 10 employed to regulate the amplitude of motion of the connecting rod 9, and therefore of the oscillation.

The lever 6 (Fig. 1) carries a roller which is rotatable on the stud *k* which engages in 15 a suitable groove, formed on the cam 4; the link 8 connects together the levers 6 and 7, which are pivoted to the respective studs *n* and *p*. Upon the lever 7 is mounted the circular sector *r* provided with a slot *s* in 20 which the end of the link 8 may be displaced and secured by means of a stud *t* having a screw-threaded end engaged by a nut *t'*.

It will be readily understood that the 25 stroke of the connecting rod 9 and hence the oscillation of the needles will be increased or diminished according to the position of the end of the link 8 upon the sector *r* of the lever 7.

Figs. 7 and 8 show two other arrangements 30 for the obtainment of the movement of the needles, while maintaining the same principle.

In both cases, the studs *e* *e'* *e''* are secured 35 to bosses formed on the cast iron head of the machine. The connecting rod 9 (Fig. 7) as in the preceding description, imparts to the lever *M* a movement of rotation about *e''*. The lever *K* is actuated by an extended part 40 *9'* of the rod 9, the lever *L* and the link *P*. This separates or brings together the bearings *c* and *d* which are secured to the levers *M* and *K*, and hence imparts to the levers 16 and 17 a suitable movement, as above de- 45 scribed.

Fig. 8 is a modified form of the preceding figure.

In this embodiment the levers *K*, *L* and link *P* are arranged as before. The extension *9'* has been eliminated, however, from rod 9 which is directly connected to lever *L*. The pivot stud *e''* has been moved to the opposite end of lever *M* which is connected to the lever *L* through a link *P'* similar to 55 the link *P*.

Obviously, modifications in detail may be made in the constructional forms above described without departing from the principle of the invention.

60 What I claim is:

1. In a sewing machine of the type described having a main operating shaft and an operating cam driven thereby, the combination of a pivoted lever reciprocated by said cam, a second pivoted lever parallelly dis-

posed to said first mentioned lever, a link pivotally connecting the free ends of said levers, means for changing one of the pivot points of said link, a pair of needle oscillating rods and a toggle mechanism operatively connected to said second lever slidably engaging said needle oscillating rods. 70

2. In a sewing machine of the type described having a main operating shaft and an operating cam driven thereby, the combination of a pivoted lever reciprocated by said cam, a second pivoted lever parallelly disposed to said first mentioned lever, a link pivotally connecting the free ends of said levers, means for changing one of the pivot points of said link, a needle oscillating rod connected at one extremity to the free end of said second lever whereby the oscillating movement of said rod may be varied at will, 80 a pair of needle rods pivotally mounted adjacent the other extremity of said rod and a toggle mechanism associated with said other extremity of said rod adapted to transmit the motion thereof to said needle rods and to cause said needle rods to move to and from each other. 85

3. In a sewing machine of the type described having a main operating shaft and an operating cam driven thereby, the combination of a pivoted lever reciprocated by said cam, a second pivoted lever parallelly disposed to said first mentioned lever, a link pivotally connecting the free ends of said levers, means for changing one of the pivot points of said link without displacing either 90 of said levers, a pair of needle oscillating rods, and a toggle mechanism operatively connected to said second lever slidably engaging said needle oscillating rods. 95

4. In a sewing machine of the type described, a main operating shaft and an operating cam driven thereby, the combination of a pivoted lever reciprocated by said cam, a second pivoted lever parallel to said first mentioned lever, a link for pivotally connecting the free ends of said levers, an arcuate slot in one of said levers, a stud pivotally connected to said link and a projection on said stud adapted to slidably engage said slot, means for fixing said projection in a given position in said slot, a pair of needle oscillating rods and a toggle mechanism operatively connected to said second lever slidably engaging said needle oscillating rods. 105 110 115

5. A sewing machine according to claim 4 in which said arcuate slot is provided along its edges with overhanging flanges embracing the projection of said stud. 120

6. In a sewing machine of the type described a plurality of pivotally mounted needle bars, a needle oscillating crossbar, a pivoted lever parallelogram pivoted to said crossbar and slidably connected to one of said needle bars at the common pivot point of two of the levers of said parallelogram and 125 130

an extension on one of the levers of said parallelogram slidably engaging the other of said needle bars for the purpose described.

7. In a sewing machine of the type described a plurality of pivotally mounted needle bars, a needle oscillating crossbar, a pivoted lever parallelogram pivoted to said crossbar and slidably connected to one of said needle bars at the common pivot point of two of the levers of said parallelogram, an extension on one of the levers of said parallelogram slidably engaging the other of said needle bars and a pivotally mounted cylinder for slidably supporting said needle oscillating crossbar.

8. In a sewing machine of the type described a plurality of pivotally mounted needle bars, a needle oscillating crossbar, a pivoted lever parallelogram pivoted to said cross-bar and slidably connected to one of said needle bars at the common pivot point of two of the levers of said parallelogram, and means projecting from one of the levers of said parallelogram slidably engaging the other of said needle bars for the purpose described.

9. In a sewing machine of the type described a plurality of pivotally mounted needle bars, a needle oscillating crossbar, a lever slidably engaging one of said needle bars at its extremity, a second lever pivoted at one extremity to the mid-point of said first lever, slidably engaging the other needle bar at its free extremity, a third lever of the same length as said second lever pivoted at one extremity to the free end of said first lever and at the other extremity to said cross bar, and a link interconnecting the extremities of said second and third levers remote from said first lever for the purpose described.

10. In a sewing machine of the type described a plurality of pivotally mounted needle bars, a needle oscillating crossbar, a pivoted lever parallelogram pivoted to said crossbar and slidably connected to one of said needle bars at the common pivot point of two of the levers of said parallelogram, an extension on one of the levers of said parallelogram slidably engaging the other of said needle bars and pivotally mounted means for slidably supporting said needle oscillating crossbar.

In testimony whereof I have signed this specification.

55 FELIX MOREL.
